United States Patent Office

Des. 224,906
Patented Oct. 10, 1972

224,906

RESTAURANT BUILDING

E. Wallace Barr, Jr., Bowling Green, Ky., assignor to Kentucky Rib-Eye, Inc., Bowling Green, Ky.

Filed Mar. 10, 1971, Ser. No. 123,119

Term of patent 14 years

Int. Cl. D25—03

U.S. Cl. D13—1

Fig. 1

Fig. 2

Fig. 3

FIG. 1 is a front elevational view of the restaurant building, made in accordance with my invention;

FIG. 2 is a rear elevation; and

FIG. 3 is a side elevation, taken from the right side of the restaurant building disclosed in FIG. 1.

The side of the building not shown is essentially the same as the side shown in FIG. 3.

I claim:

The ornamental design for a restaurant building, as shown and described.
